NONGLARE ROAD AND CAR ILLUMINATING HEADLIGHT

Filed May 4, 1925

INVENTOR.
WILLIAM D. BAKER

BY *Fred D. Hayes*

ATTORNEY.

UNITED STATES PATENT OFFICE.

WILLIAM D. BAKER, OF TRONA, CALIFORNIA.

NONGLARE ROAD AND CAR ILLUMINATING HEADLIGHT.

Application filed May 4, 1925. Serial No. 27,825.

My invention relates to illuminating mechanisms and devices, both for stationary and moving objects or supports, or intermittently moving and stationary objects or supports, such as rooms, statues, land, air, or water craft, and the like, in which said stationary or moving, or intermittently moving and stationary objects or supports are adapted to be illuminated in all directions except upwardly, but without any portion of said illuminating means being visible at any time from a point at or near that at which the eye of the casual observer is ordinarily positioned.

As is well known, the illuminating mechanisms and devices now in common use have the serious defect of casting an objectionable glare into the eyes of the casual observer. This is especially so when said illuminating means is used on land, air, or water craft, the casual observer being frequently temporarily blinded by the glare from said illuminating means, said observer, either when on said craft or outside thereof being bewildered so as actually to involve collisions with resulting more or less serious accidents. By the use of my invention all these objectionable features are eliminated, providing comfort and at the same time the best possible illumination.

It accordingly is an object of my invention to provide an improved illuminating device or apparatus in which rays of light are adapted to be projected forwardly, downwardly, rearwardly, or at each side thereof, but not upwardly, thus thoroughly and effectively illuminating not only the object, either stationary or moving, or intermittently stationary and moving, with which it is associated, and also the space surrounding the same, and the path of movement, but without any objectionable glare being cast into the eye of the casual observer.

A further object of my invention is to provide a novel form of illuminating means in which a casing is equipped with a light source, positioned in any convenient manner in said casing sets of light-accentuating and light-reflecting means being provided in said casing, both of said means, if desired, being adjustable, or certain of said means only being adjustable, said means effectively afford-

ing an efficient illuminating means, and at the same time obviating entirely all objectionable glare.

It is also within the province of my invention to equip my novel form of illuminating means, especially when used in connection with land, air, or water craft, with a danger signal positioned on the left side of said means, and also a subdued light signal preferably positioned forwardly thereof.

A still further object of my invention is to equip my novel form of lamp with buffer or cushioning means, and also an adjustable mechanism, said means and mechanism being so associated with said lamp and its support, that said lamp may be adjusted both longitudinally and transversely relative to said support, and both longitudinally and transversely cushioned with respect to all vibrations or shocks to which said standard may be subjected.

It is moreover within the province of my invention to equip my novel form of illuminating means, especially when said means is used on a moving object, or intermittently movable and stationary object, with an adjustable balancing means provided with a suitable stop mechanism, whereby said means may be continually held stationary irrespective of any movement or vibration of the support with which said means may be associated. If desired said balancing means may be in the form of a hollow member, either partly, or almost entirely filled with mercury or other material to form such balancing means.

It is also an object of my invention to provide a novel form of illuminating means which is simple in character, attractive in appearance, thoroughly reliable and effective in operation, durable, composed of a minimum number of parts, easy and inexpensive to manufacture, not easy to get out of order, and which will thoroughly and effectively produce the objects intended.

Further objects and advantages of my invention will become more apparent as the description thereof proceeds.

Reference is had to the accompanying drawings, in which similar reference characters denote similar parts. In the drawings Fig. 1 is a front elevational view of a

motor vehicle showing my invention applied thereto, with a suggested mounting therefor,

5 Fig. 2 is a longitudinal sectional view of one form of my improved lamp, showing the manner in which the light rays are projected therefrom,

Fig. 3 is a similar view of a modification,

10 Fig. 4 is a side elevational view of one form of my illuminating means with a balancing means applied thereto;

Fig. 5 shows a fragmentary side elevational view showing another application of my invention,

15 Fig. 6 is a front elevational fragmentary view of my improved lamp and a modified form of mounting therefor,

Fig. 7 is a fragmentary detail view of one 20 of the arms associated with the standard upon which my improved lamp is adapted to be mounted, and

Fig. 8 is a similar view on a very much enlarged scale than that shown in Fig. 7.

Describing my invention more in detail, V 25 indicates a motor vehicle, the head lights H of which embody my improvements. It will be observed that I have positioned said head lights higher than is usually done in practice, for the reason that it will be possible 30 to more effectively illuminate both the road and the vehicle itself. In practice I may raise said lights even higher or in fact lower the same, as may be found expedient.

If desired, the head lights H may be in the 35 form of a casing C of any preferred shape, or constructed as shown, and formed out of any suitable material. Positioned in one end of said casing is a light source S, of any character preferred, which light source may 40 be positioned in either end of said casing. If preferred, said casing may be made in sectional form, as shown in Fig. 3, providing a convenient and easy means for adjusting the various parts of said casing relative to the light source S, which adjustable means may take any form preferred. The 45 light source may be in the form of an electric light bulb, or a set of such bulbs, of any suitable candle power, said illuminating 50 means having associated therewith a light accentuating means of any preferred construction or shape, in the present instance being shown as a parabola, either in sectional form, or one single and rigid construction.

The internal surface of the casing C may 60 be in the form of an elongated structure having a reflective surface, or separate and distinct reflectors of any preferred type or construction may be substituted therefor, said reflectors being adapted to project the rays of light forwardly, downwardly, rearwardly or to either side, thus forming an efficient means for not only illuminating the 65 object, either stationary or moving, or in-

termittently stationary and moving, with which it may be associated but also the path of movement of said moving object, both forwardly and rearwardly.

It will be observed that the special feature of my invention is to provide an efficient means for preventing the glare of the illuminating means from reaching the eyes of the casual observer, with often the disastrous results hereinbefore referred to. To 75 make this feature more effective, I may provide the casing C with one or more additional reflectors, thoroughly covering the light source S from the eyes of the observer, but at the same time without lessening the 80 effectiveness of said source; to the contrary the mirror or reflector M, which may be of any preferred construction and shape, and be positioned on said casing at any desired point or angle, increases the effectiveness 85 of such light source, casting the rays of light emanating from said source downwardly and rearwardly, as more particularly shown in Figs. 2 and 5.

If desired, the mirror M may have associated therewith in any preferred manner a magnifying lens 4 of any suitable character, size and construction, and placed at an angle or otherwise, said lens increasing the effectiveness of the light source S. It 90 is my purpose also to equip one of the head lights H with a danger signal R in the shape of a red lens to warn approaching vehicles, and also equip said casing with a 100 lens 2 of a green or other color, forming a subdued light signal. It will be obvious also that if desired a suitable glass closure may be provided for the casing C to prevent dust and other extraneous matter from accumulating in said casing and soiling the 105 reflector 1 or the sets of reflectors or light sources associated with said casing.

In Fig. 3 I have shown such a glass protective element L and a means either for hingedly associating said element with a 110 casing C', or using a conventional form of snap fasteners. In the form shown in Fig. 3, the casing is formed of a sectional construction 3 of such a form that the various sections may be adjusted toward or away 115 from the light source or sources S', having associated therewith a reflector 1' of any preferred type, the interior of said casing being formed with a reflective surface or reflectors of any type secured thereto in any 120 desired manner, and adjustable toward and away from said light source or sources. The casing C' is also equipped with a mirror M' and a lens 4 similar to those associated with the form shown in Fig. 2. Said 125 casing is also equipped with a danger signal R' and a subdued light signal 2' of any preferred type. It will be understood that the head light H on the right of the vehicle, or the head light facing traffic approaching 130

from the right, will not be provided with a danger signal, if desired, such head light may however, be equipped with a subdued light signal such as a lens 2'.

5 In Fig. 4 I have shown a balancing means B, which may be either partially or almost entirely filled with mercury, or of solid construction, to provide a means for balancing my improved lamp when the vehicle 10 or craft with which it is associated is suddenly moved upwardly or downwardly, an adjustable screw-threaded stop means D being provided on the standard 5 to limit and adjust the position of said balancing means, 15 which means may be of any preferred type or construction.

In Fig. 5 I have shown a stationary object in the form of a statue S' of any desired character, as provided with a lamp 20 H'' equipped with a subdued light signal 2'', positioned forwardly thereof as shown, and also equipped with a mirror M'' functioning in the manner hereinbefore explained. As will be obvious, the entire 25 statue or object will be enveloped with light, but without any objectionable glare reaching the eyes of the casual observer. It will also be clear that the lamp H'' may be associated with sign boards, or may be positioned in dwellings or other buildings, and 30 form a markedly efficient illuminating means providing comfort and light for the occupants of said buildings.

In Figs. 6 to 8 I have shown a special 25 manner for mounting my improved lamp, the standard of which may be associated with its support in any preferred manner. For example, the standard 5 in Fig. 1 may be shortened and secured to a cross bar 40 across the front of the vehicle, or the head lights H may be mounted on the fender; in short, said head lights and standards may be associated with the vehicle in any manner preferred.

45 Of course, the particular manner in which my improved lamp is mounted is immaterial, so long as all shocks or vibration due to road travel are effectively prevented from reaching said lamp, thereby increasing the 50 life of said lamp materially. If preferred, said lamp may be mounted in a frame f, with a tension means for adjusting the position of said lamp both transversely and longitudinally with respect to its mounting. 55 Moreover, cushioning means in the form of rubber buffer members, or indeed, springs of any resiliency may be used instead.

A convenient means for preventing shocks 60 and vibration from reaching the lamp is shown more particularly in Fig. 8, in which the frame f is equipped with a flange 11, and a pair of buffer members 7 are placed above and below the projection 14 on the lamp, a flange 9 being formed on said projection to which the casing C of the lamp

may be secured, or said flange 9 may be formed integral with said casing. If desired also buffer or spring means may be positioned between the flange 9 and the casing C. A tension spring 12 is coiled 70 about the outer end of the detachable bolt 15, and a nut 8 is used to adjust the tension of said spring. Similarly, a nut 10 of any preferred type may be used to adjust the tension of the buffer or spring members 7, 75 which may be made of any desired composition, or ordinary springs may be substituted therefor.

As shown in Fig. 8 also, the projection 14 has positioned therein a detachable bolt 15 which has its outer end encircled by the helical spring 12 engaged by the nut 8, and the frame f is provided with a slot of a sufficient size as to accommodate the bolt 15, which projection is also slotted so that the casing C may be cushioned both transversely and longitudinally to prevent any shocks of vibrations in all directions from reaching said casing to prevent damage thereto, the projection 14 being equipped 90 with a flange associated in any preferred manner with the flange 9 of the casing.

In Fig. 6 the lamp H'' is also provided with a danger signal R'', and a subdued light signal in the form of a green, yellow, 95 blue, or any other preferred color, lens 2'', though these are optional. Said lamp is also equipped with a mirror M'', functioning as in the other forms of my invention. It may also be stated that the lamp may be supported near the top, so that the weight of said lamp will be below its point of support.

While I have thus described my invention with great particularity, it will be clear that the same may be modified throughout a wide range. I therefore do not propose to be limited to the exact details of construction shown and described, but reserve the right in practice to make any and all modifications thereof that fall within the scope of the appended claims.

I claim as my invention:

1. A non-glare illuminating means comprising in combination an elongated casing, 115 a light source in said casing, a reversely positioned mirror in said casing for reflecting rearwardly the rays of light from said light source and also for excluding the rays of light from said light source from the eyes of the casual observer, a lens positioned on the upper end of said mirror, and a set of reflectors in said casing for reflecting the rays of light from said light source in all directions except upwardly and rearwardly. 125

2. A non-glare illuminating means comprising in combination a casing having upper and lower forwardly projecting portions, said upper portion extending a substantial distance beyond said lower portion, 130

- a reversely positioned mirror secured to the outer end of said lower portion, a lens on the upper end of said mirror, a light source in one end of said casing, said light source being adapted to cast rays of light through said lens and also to said mirror for reflecting the same rearwardly, and a set of reflectors in said casing whereby the rays of light from said light source may be cast in all directions except upwardly and rearwardly, none of which will reach the eyes of the casual observer.
3. A non-glare lamp comprising in combination a casing having an upper portion formed of hinged sections and a stationary lower portion, said upper portion extending a substantial distance beyond said lower portion, a transparent closure for the opening in said casing defined by said portions, a light source in said casing, a reflector associated with said light source, said hinged sections having their inner portions formed with light reflecting surfaces, a subdued light signal positioned in the forward part of said upper portion, a danger signal in one side of said upper portion, and means on said lower portion for preventing objectionable rays from said light source reaching the eyes of the casual observer.
4. A non-glare head light adapted for use on vehicles comprising in combination a casing, said casing having upper and lower portions, said upper portion extending a substantial distance beyond said lower portion, a light source in said casing, means an said lower portion for excluding the rays of light from said light source from the eyes of the casual observer, reflectors in said casing for illuminating said vehicle and the roadway both forwardly and laterally, and adjustable means associated with said head light whereby said head light will always be so positioned that the rays of light from said light source, will not reach the eyes of the casual observer, irrespective of the position of said vehicle.

In testimony whereof I have signed my name to this specification.

WILLIAM D. BAKER.
